UNITED STATES PATENT OFFICE.

REVERDY P. SMITH, OF NEW HAVEN, CONNECTICUT.

TOY.

1,266,874.

Specification of Letters Patent. Patented May 21, 1918.

Application filed September 13, 1917. Serial No. 191,204.

To all whom it may concern:

Be it known that I, REVERDY P. SMITH, a citizen of the United States, residing at New Haven, in the county of New Haven 5 and State of Connecticut, have invented a new and useful Improvement in Toys; and I do hereby declare the following, when taken in connection with the accompanying drawings and the characters of reference 10 marked thereon, to be a full, clear, and exact description of the same, and which said drawings constitute part of this application, and represent, in—

Figure 1 a side view of a toy constructed 15 in accordance with my invention.

Fig. 2 a top or plan view of the same, with the car removed.

Fig. 3 a broken view of the bottom portion of the car showing a front view of 20 the gripper pin, and tripping plate.

Fig. 4 a diagrammatical view indicating the use of an electric motor.

This invention relates to an improvement 25 in toys of the inclined railway or loop the loop type, the object of the invention being to produce a mechanical toy in which a car may be drawn to the highest point, and then run by force of gravity until it strikes the main incline, where it will start 30 the operating mechanism to draw the car up to the top of the incline, with provision for the car to stop the operating mechanism as it starts on its downward trip; and the invention consists in the construction hereinafter described and particularly 35 recited in the claims.

In carrying out my invention, I employ a track or runway 6 which includes a steep 40 upward incline 7 from the top of which it extends downward abruptly, then bowed to form a loop 8 from which the track extends gradually upward, and then slightly downward to the bottom of the upward incline 7. This track is formed from one or more 45 strips of sheet metal of suitable length and is supported by a base 9 with uprights 10 and 11 on which the track rests. At the bottom of the incline 7 is mounted an idler 12, and at the top of the incline is an idler 13, these idlers projecting through clearance 50 slots 14 and 15 formed for them in the center of the track. Passing over these idlers and over the upper face of the track and around a sprocket wheel 16 is an end- 55 less chain 17. The sprocket wheel 16 may be driven by any suitable means as a spring

motor 18, as indicated in Fig. 2 of the drawings, or an electric motor 19, as indicated in Fig. 4 of the drawings. The spring motor will include a stop wheel 20 and a 60 stop lever 21. This stop lever will be connected by a cord or wire 22 with a bell-crank starting lever 23 mounted below the track at the bottom of the incline 7, one arm 24 of the lever extending upward 65 through a clearance slot 25 formed for it. At the top of the incline is a clearance slot 26 through which projects the upper end of a stopping lever 27 the lower end of which engages the operating arm 28 of a rock 70 shaft 29 which is provided with a crank arm 30 connected by a cord or wire 31 with the tripping lever 21. The car 32 forming a part of this toy, may be of any approved design, and is provided with wheels 75 33 having flanges 34 to set over the outside edges of the track. Pivotedly connected with the bottom of the car is a gripper pin 35 on which is a tripper plate 36. If an electric motor is employed, as indicated 80 in Fig. 4, the starting lever 37 corresponding to the starting lever 23, will, when moved forward, close the circuit so as to start the motor. Then when the stopping lever 38 corresponding to the lever 27, is 85 moved forward it will actuate the rod 39 and move the lever 37 to open the circuit. The spring motor being in condition for operation, the car 32 is started at the bottom of the 90 incline, or placed upon the chain 17 so that the gripper pin 35 engages with one of the links of the chain. The starting lever 23 or 37 will then be moved to start the motor, and this will move the chain 95 so as to draw the car to the top of the incline. As it reaches the top of the incline, the tripper plate 36 engages with the upper end of the stopping lever 27 or 38 so as to stop the motor and arrest the movement 100 of the chain. The car by momentum will start down the incline, loop the loop, and run onto the incline portion 7, and as it passes the starting lever 23 or 37, the tripper plate 36 will move those levers and 105 start the motor, the car passing onto the incline so that the gripper pin 35 engages one of the links of the chain. The car will then continue to make the circuit of the track.

I claim:—

1. A toy comprising an inclined track

having reversely inclined surfaces, a car adapted to run upon the said track, a chain adapted to draw the car up the primary incline, mechanism for driving the chain, and means operated by the car for starting and stopping the operating mechanism.

2. A toy comprising a track having reverse inclines and a circular bend, a car adapted to run upon said track, a chain 10 passing over the upward incline, means for driving said chain, and means operated by the car for starting and stopping the chain-operating means.

3. A toy comprising a track having reverse inclines, a car adapted to run upon said track, said car provided with a downwardly projecting gripping pin, and a tripping plate, a motor including a sprocket wheel, idlers at the bottom and top of the

upward incline, an endless chain passing 20 around the sprocket wheel and idlers, and over the upper surface of the upward incline, a starting lever projecting upward through the track at the bottom of the incline, a stopping lever projecting upward 25 through the track at the top of the incline, the tripping plate adapted to actuate the starting and stopping levers, and connections between the starting and stopping levers and the motor for starting and stopping the same.

In testimony whereof, I have signed this specification in the presence of two subscribing witnesses.

REVERDY P. SMITH.
